ATTORNEY

UNITED STATES PATENT OFFICE

MARY E. JAQUES, OF LINCOLN, NEBRASKA

KNOT FASTENER FOR SHOE STRINGS

Application filed May 18, 1928. Serial No. 278,831.

This invention relates to certain novel improvements in knot fasteners for shoe strings, and has for its principal object the provision of an improved construction of this character, which will be highly efficient in use and economical in manufacture.

Among the objects of my invention is the provision of a device of the foregoing character which should be arranged such that it may be expeditiously installed in operable position and one which will not inconvenience the user by causing irritation of parts of the body which may be juxtaposed to the fastener.

Other objects will appear hereinafter.

15 The invention consists in the novel combination and arrangement of parts to be hereinafter described and claimed.

The invention will be best understood by reference to the accompanying drawings, 20 wherein a preferred form of construction is shown, and in which:

Fig. 1 is an elevational view depicting a preferred embodiment of my invention in operating position;

25 Fig. 2 is a perspective view depicting my improved knot fastener;

Fig. 3 is a longitudinal sectional view of the device illustrated in Fig. 2;

Fig. 4 is a sectional detail view taken substantially on the line 4—4 on Fig. 3; and

Fig. 5 is a view substantially similar to Fig. 4 depicting a modified form of construction.

In the drawings, wherein a preferred embodiment of my invention is illustrated, 35 10 indicates the knot tied adjacent the ends of a shoe lace 11 which is shown at Fig. 1 as being associated with a shoe 12, which includes a protecting tongue 13. The device is adapted to be inserted around the knot 10 and one edge thereof rests on the tongue 13 and as will be described more fully herein-after, this edge is shaped so as to alleviate the likelihood of irritation to the user's foot.

40 45 My improved device comprises a back plate 14 which preferably embodies a formation substantially similar to that indicated in Fig. 3 wherein it will be seen that there is a curved portion intermediate the ends thereof and that the forward end is disposed at a

higher level than the rear end. Adjacent the rear end of the plate 14, and adapted to extend at right angles thereto along the edges thereof, are upstanding ears 15, which have openings such as 16 provided therein. In 55 the embodiment of the invention illustrated in Figs. 2, 3 and 4, the top plate 17 of my device is arranged so as to embody a substantially circular configuration longitudinally thereof which terminates in a downwardly depending portion 18. Adapted to be struck from the side walls of the plate 17 adjacent the juncture between the downwardly depending portion 18 and the curved upper surface thereof, are outwardly extending ears 60 19 which are adapted to be inserted into the opening 16, in order that the plate 17 will be pivotally associated with the plate 14. The side walls 20 of the device are serrated as indicated at 21 along their lower edges, 70 for a purpose now to be made apparent.

In using the device, the plate 14 is inserted below the knot and the upper plate 17 is moved into position such that the portions of the laces adjacent the knot will be gripped by the serrated portions 21. The downwardly depending portion 18 will engage the inner side of the plate 14 adjacent the rear end thereof which preferably curves upwardly as indicated at 22 and therefore, substantially cam like action will result when the portion 18 engages this portion 22. Due to the thickness of the material between the upper side of the plate 14 and the serrated portions 22 and the foregoing mentioned cam action, the device will be securely locked into position and thus retain the knot from becoming untied.

85 90 95 In Fig. 5, a modified form of construction is shown. Herein the back plate 14 is formed substantially similar to the back plate depicted in Figs. 2, 3 and 4. The top plate 23 in this instance is arranged so as to include a portion 24 at the rear end thereof which is bent so as to extend parallel with the plate 23 for a pre-determined distance and this portion 24 terminates in a downwardly depending portion 25. Ears 26 are struck from this downwardly depending portion that are adapted to be mounted in the openings 26. 100

The side walls of the plate 23 are serrated as indicated at 27 and this device forms in substantially the same manner as the device illustrated in Figs. 2, 3 and 4 and in this 5 instance, the lower end of the portion 25 co-operates with the formed portion 22 to produce the cam action.

While I have illustrated and described the preferred form of construction for carrying 10 my invention into effect, this is capable of variation and modification, without departing from the spirit of the invention. I, therefore, do not wish to be limited to the precise details of construction set forth herein, but desire to avail myself of such variations and modifications as come within the scope of the appended claim.

Having thus described my invention, what 20 I claim as new and desire to protect by Letters Patent is:

A device of the character stated including a bottom plate having a curved configuration extending longitudinally thereof whereby one end portion thereof will be disposed at a 25 higher level than the other end portion thereof, said bottom plate having upwardly extending ears formed on the sides thereof at the lower end, a top plate having depending side portions on the lateral edges thereof, 30 the lower side of said depending flanges being serrated, said top plate including a portion at the end thereof disposed above the ears on said lower plate bent forwardly therealong on the under side thereof for a short 35 distance and then bent downwardly into engagement with said bottom plate, said ears on said bottom plate having openings formed therein, and lugs formed on the downwardly projecting portion of said top plate disposed 40 in said openings to pivotally interconnect said top plate to said bottom plate whereby when the serrations on said top plate engage a shoe lace or the like arranged intermediate 45 said plates the downwardly extending portion of said top plate will be forced into engagement with said bottom plate to secure said top plate in clamping position with respect to said shoe lace.

In testimony whereof I affix my signature.
50 MARY E. JAQUES.
